UNITED STATES PATENT OFFICE.

HENRY A. STEARNS, JR., OF MILFORD, MASSACHUSETTS.

MACHINE FOR POLISHING RINGS.

No. 847,445.

Specification of Letters Patent.

Patented March 19, 1907.

Application filed January 4, 1907. Serial No. 360,767.

To all whom it may concern:

Be it known that I, HENRY A. STEARNS, Jr., a citizen of the United States, residing at Milford, in the county of Worcester and State of Massachusetts, have invented new and useful Improvements in Machines for Polishing Rings, of which the following is a specification.

This invention relates to a machine for polishing the inner surfaces of rings, and is particularly adapted for polishing the inner surfaces of spinning and twister rings, such as are used in connection with textile machinery.

The object of the invention is to provide a simple, compact, and easily-operated machine which is adapted to hold a variety of sizes and widths of rings which are to be polished and which is also adapted to be easily changed, so that different-sized rings may be inserted in the machine to be polished.

The object of the invention is, further, to provide a machine which will do the work hereinbefore set forth economically and quickly.

The invention consists in the combination and arrangement of parts set forth in the following specification and particularly pointed out in the claims thereof.

Referring to the drawings, Figure 1 is a front elevation of my improved machine for polishing rings, broken to save space. Fig. 2 is a vertical longitudinal section, partly in elevation, of the lower portion of the machine, comprising that part of the machine which performs the polishing operation. Fig. 3 is a sectional elevation taken on line 3 3 of Fig. 2 looking toward the left in said figure. Fig. 4 is a side elevation of a form used in adjusting the machine to the size of rings which are to be polished therein.

Like numerals refer to like parts throughout the several views of the drawings.

In the drawings, 5 5' are the frame-stands, which may be fastened to a bench or to a table. 6 is a counter-shaft supported in bearings in said side frames and having fastened at its opposite ends pulleys, 7 and 8. The shaft 6 may be driven either by a pulley or by hand. The pulley 7 is connected by a cross-belt 9 to a pulley 10, fast to a driving-shaft 11, which is journaled to rotate in a bearing provided in the side frame 5 and terminates in a pointed end 12 at the inner side of the frame. The pulley 8 is connected by a

straight belt 13 to a pulley 14, fast to a driving-shaft 15, which terminates at the inner side of said frame 5 in a pointed end 16. A polisher-shaft 17 is supported upon said pointed ends 12 and 16 and has fastened thereto a polishing-pad 18 by means of a bolt 19, which extends through said polishing-pad and through the polisher-shaft 17. The polishing-pad 18 is preferably formed of felt, the two ends of said felt being doubled partly around the shaft 17 and fastened thereto by the bolt 19, as hereinbefore set forth. The polishing-pad 18 is eccentric to the shaft 17 and bears along its outer face against the inner faces of the rings 20 20.

The rings 20 20 are of the form used for spinning and twister rings and have flanges 21 21, projecting inwardly therefrom, as well as flanges 22 22, projecting outwardly therefrom. The rings 20 are held in position to be polished by a holder 23, which consists of two end plates 24 25, joined together and adjustable toward each other by means of bolts 26 26. Said bolts are screw-threaded and provided with nuts 27 28 at the opposite ends thereof, whereby the rings 20 may be clamped between said end plates. Said end plates are preferably provided upon their inner faces with steel disks 29, fastened thereto for the purpose of resisting wear.

In order to adjust the rings 20 and to hold them concentric with the shaft 17, clamp-blocks 30 30 are provided, preferably made of wood, and are held against the peripheries of said rings by means of adjusting-screws 31 31, the inner ends of which bear against or project into said clamp-blocks, said adjusting-screws having screw-threaded engagement with annular plates 32 32, which extend around said rings between the end plates 24 and 25 and are supported by the bolts 26 26. Said adjusting-screws are locked to the annular plates 32 32 by means of lock-nuts 33 33.

The holder 23 as a whole is prevented from moving longitudinally upon the shaft 17 at one end thereof by a collar 34, which is fastened to the shaft 17 and bears against the outer face of the end plate 24. The end plate 25 has holes provided therein to receive a plurality of pins 35, fast to a sleeve 36, which in turn is rigidly fastened to the shaft 11. The shaft 17 is rotated by the driving-shaft 15, said shaft 17 having a dog 37 fast thereto and slotted at its opposite ends at

38 38 to receive pins 39 39, fast to a plate 40, which in turn is fastened rigidly to the driving-shaft 15.

The driving-shaft 15 is rendered movable 5 longitudinally thereof in the end frame 5' by removing the cotter-pin 41 from the collar 42 and from said shaft 15.

A bushing 43 is fastened to the end plate 24 and projects therethrough into the interior of the holder 23 and between the felt 18 and the shaft 17. A similar bushing 44 is provided at the left-hand end of the holder 23, Fig. 2, said bushing 44 being fastened to the end plate 25.

It will be noted that the clamp-blocks 30 are made shorter than the sum of the widths of the different rings 20, inclosed between the end plates 24 25, so that said nuts 28 can be screwed upon the bolts 26 to clamp 20 the rings 20 firmly together without said end plates abutting against said clamp-blocks. It will further be noted that by adjusting the screws 31 rings of different diameters may be clamped in the same holder and that 25 by varying the length of the bolts 26 26 a larger or smaller number of rings may be accommodated in the holder. For the purpose of illustration only nine rings are shown in the drawing; but in machines as practically 30 used fifty rings can be used on one holder to advantage.

In polishing the rings the space not occupied by the polishing-pad in the interior of said rings is filled with emery 47, preferably of different-sized grains, the most desirable sizes having been found to be Nos. 10 and 18.

To remove the holder for the purpose of taking out rings which have been polished 40 and reloading the same, the cotter-pin 41 is removed, and the shaft 15, together with the plate 40 and the pins 39, are moved toward the right, Fig. 2, releasing the dog 37, so that said dog and the shaft 17, together with the 45 holder 23, attached thereto, may be moved toward the right a sufficient distance to remove the end plate 25 from the pins 35, the left-hand end of the shaft 17 at the same time being removed from connection with 50 the pointed end 12 of the shaft 11. Having thus removed the holder from the machine, the dog 37 is removed from the shaft 17. The collar 34 is also removed from said shaft 17, and the nuts 28 28 28 are removed from 55 their respective bolts 26 26 26, so that the end plate 24 can be removed from said bolts and from the shaft 17. The emery is then emptied out from the interior of the rings 20 20, the shaft 17 removed, and the set-screws 60 31, which bear against one of the clamp-blocks 30, are loosened. This will free the rings from the pressure of the blocks, and they can then be removed from the interior of the holder.

65 In reloading the holder a new set of rings

are placed in said holder inside the clamp-blocks 30 30 30. The block 30 which has previously been loosened is tightened against the rings by tightening the set-screws 31 31 31, the shaft 17 is inserted in its proper 70 place, and the space not occupied by the pad 18 in the inside of the rings is filled with emery 47. The outside plate 24 is then placed in position and screwed up by means of the nuts 28 28 to clamp the rings 20 in 75 place, the collar 34 is then placed in position and tightened by its set-screw, and the dog 37 is securely fastened to the shaft, and the holder is then ready to be placed in the machine, which is done by slipping the end 80 plate 25 upon the pins 35 35 and then moving the shaft 15 until its pointed end abuts against the adjacent end of the shaft 17, while the pins 39 39 enter the slots 38 38 in the dog 37. The collar 42 can be secured by 85 slipping the cotter-pin 41 through the hole provided therefor in the shaft 15, thus placing the machine in readiness to polish a new set of rings.

To enable the operator to readily adjust 90 the machine to sets of rings of varying diameters, a cylindrical form 45 is provided for each set of rings of different diameters. Said form has a pin 46 projecting from one end thereof, which is of the same diameter as 95 the shaft 17 and is inserted in the hole provided therefor in the end plate 25. The clamp-blocks 30 are then adjusted to bear against the periphery of the form 45 by adjusting the screws 31 31 sufficiently so to do. The form is then removed by loosening the 100 set-screws 31 31 for one clamp-block, and the holder is then in readiness for the rings of the diameter of the form 45 to be inserted in the holder.

The general operation of the device hereinbefore specifically described is as follows: Assuming that the shaft 6 is rotated by suitable means, either by hand or by a pulley attached thereto, it will be seen that the shafts 11 and 15 will rotate in opposite directions, the pulleys 7 and 10 being of suitable size relatively to the pulleys 8 and 14 to cause the shaft 11 to rotate more rapidly than the shaft 15, the comparative sizes of pulleys 115 shown in the drawings having been found preferable, though not essential, to the practical operation of the machine. As the shafts 11 and 15 rotate in opposite directions, it will be seen that the shaft 17, with its polishing-pad attached thereto, and the holder 23 will rotate in opposite directions, so that the rings 20 will rotate in the direction in which the holder 23 rotates, said rings being clamped thereto, while the shaft 17 and its polishing-pad will rotate in the opposite direction to that in which said holder is rotated, thus greatly increasing the relative speed with which the pad passes over the inner surfaces of the rings 20 20. After the 120

machine has been run a short time the rings will have become polished upon their inner surfaces, and the same may be removed and new rings placed in position to be polished in a manner hereinbefore described. The polishing action takes place, as will be readily understood, by the rubbing of the emery 47 against the inner surfaces of the rings by the felt pad 18.

Having thus described my invention, what I claim, and desire by Letters Patent to secure, is—

1. In a machine for polishing rings, a holder for said rings, mechanism to rotate 5 said holder, a shaft, and a polishing-pad fast to said shaft and eccentric thereto, said pad located inside said rings and adapted to bear against the inner faces thereof.

2. In a machine for polishing rings, a holder for said rings, a shaft, a polishing-pad fast to said shaft and eccentric thereto, said pad located inside said rings and adapted to bear against the inner faces thereof, and mechanism to rotate said holder and shaft in 25 opposite directions.

3. In a machine for polishing rings, a holder for said rings, mechanism to rotate said holder, a shaft, and a polishing-pad fast to said shaft, said pad located inside said 30 rings and adapted to bear against and extend partly around the inner faces of said rings.

4. In a machine for polishing rings, two driving-shafts, each terminating in a pointed 35 end, a polisher-shaft resting at the opposite ends thereof upon said pointed ends, means to lock said polisher-shaft to one of said driving-shafts, a polishing-pad fast to said polisher-shaft, a holder for said rings, and means 40 to lock said holder to the other of said driving-shafts.

5. In a machine for polishing rings, a holder for said rings comprising two end plates, bolts connecting said end plates together, annular plates extending around said 45 rings and supported on said bolts, adjusting-

screws on said annular plates, and clamp-blocks adapted to bear against the peripheries of said rings and located between said annular plates and rings, against which 50 blocks, the inner ends of said screws bear.

6. In a machine for polishing rings, a holder for said rings comprising two end plates, bolts connecting said end plates together, annular plates extending around said 55 rings and supported on said bolts, adjusting-screws on said annular plates, and clamp-blocks adapted to bear against the peripheries of said rings and located between said annular plates and rings, against which 60 blocks the inner ends of said screws bear; in combination with a polisher-shaft extending through said plates and rotatable therein, and a polishing-pad fast to said polisher-shaft and adapted to bear against the inner 65 faces of said rings.

7. In a machine for polishing rings, a holder for said rings comprising two end plates, bolts connecting said end plates together, annular plates extending around said 70 rings and supported on said bolts, adjusting-screws on said annular plates, and clamp-blocks adapted to bear against the peripheries of said rings and located between said annular plates and rings, against which 75 blocks the inner ends of said screws bear; in combination with a polisher-shaft extending through said end plates and rotatable therein, a polishing-pad fast to said polisher-shaft and adapted to bear against the inner faces 80 of said rings, and two driving-shafts, one of said driving-shafts adapted to be locked to said polisher-shaft, the other adapted to be locked to said holder.

In testimony whereof I have hereunto set 85 my hand in presence of two subscribing witnesses.

HENRY A. STEARNS, JR.
